(57) **CLAIM**

The ornamental design for a landscaping block, as shown and described.

DESCRIPTION

FIG. 1 is a top perspective view of an embodiment of a landscaping block;

FIG. 2 is a top plan view thereof;

FIG. 3 is a bottom plan view thereof;

FIG. 4 is a front elevational view thereof;

FIG. 5 is a back elevational view thereof;

FIG. 6 is a right side elevational view thereof;

FIG. 7 is a left side elevational view thereof;

FIG. 8 is a top perspective view of a variant of the landscaping block of FIGS. 1 to 7;

FIG. 9 is a top plan view thereof;

FIG. 10 is a bottom plan view thereof;

FIG. 11 is a front elevational view thereof;

FIG. 12 is a back elevational view thereof;

FIG. 13 is a right side elevational view thereof; and,

FIG. 14 is a left side elevational view thereof;

FIG. 15 is a top perspective view of a variant of the landscaping block of FIGS. 1 to 7;

FIG. 16 is a top plan view thereof;

FIG. 17 is a bottom plan view thereof;

FIG. 18 is a front elevational view thereof;

FIG. 19 is a back elevational view thereof;

FIG. 20 is a right side elevational view thereof; and,

FIG. 21 is a left side elevational view thereof.

The broken lines in the figures depict portions of the landscaping block that form no part of the claimed design.
